atty.

UNITED STATES PATENT OFFICE

ERNEST J. LIEBETRAU, OF NILES, MICHIGAN, ASSIGNOR TO THE KAWNEER COMPANY,
OF NILES, MICHIGAN, A CORPORATION OF MICHIGAN

WINDOW CONSTRUCTION

Application filed July 14, 1930. Serial No. 467,770.

This invention relates to window constructions, and more in particular to a novel double-hung window construction, in which the sash members and the frame are constructed as a unit, and adapted to be assembled in a structure, such as a ship, etc.

Among the objects of the present invention is to provide novel sash constructions slideable in a frame. The invention comprehends the construction of such slideable sash members of metal, both of which are slideable upwardly to provide an opening of desired size.

A further object of the invention is to provide a window construction in which the lower sash may be raised through its entire height, and if it be desired to provide an opening of greater size, all that is necessary is to continue to raise the lower sash, such lower sash carrying along therewith the upper sash, so that both sashes may be raised to provide an opening of the combined size of said sashes, or an opening of any intermediate size.

A still further object of the invention is to provide means on an upper sash adapted to be engaged by a part of the lower sash whereby when the lower sash is raised to an extent substantially equal to its height, a further raising or opening of the lower sash, causes an engagement of said part by the lower sash and raises the upper sash to any desired height.

Another object of the invention is the provision of a novel window frame and sash construction, the window structure being built as a unit and adapted to be placed in a ship or building opening, and there mounted or held in position.

Another object of the invention is to provide a novel construction of sash member provided with a removable top rail for facilitating glazing of the sash.

Further objects are to provide a construction of maximum simplicity, efficiency, economy, and ease of assembly, operation and maintenance; and such further objects, advantages, and capabilities as will later more fully appear and are inherently possessed thereby.

The invention further resides in the com-

bination, construction and arrangements of parts illustrated in the accompanying drawing, and while I have shown therein a preferred embodiment, it is to be understood that the same is susceptible of modification and change, without departing from the spirit of the invention.

In the drawing:

Fig. 1 is a view in side elevation disclosing the exterior of the window construction.

Fig. 2 is a fragmentary view in vertical cross section taken in the plane represented by the line 2-2 of Fig. 1.

Fig. 3 is a fragmentary view in horizontal cross section taken in the plane represented by the line 3-3 of Fig. 1.

Fig. 4 is a fragmentary view in side elevation of the corner of the sash member.

Referring more particularly to the drawing, the embodiment selected to illustrate the invention comprises the hull or metal plate 1 of a ship, in an opening of which is mounted the window frame designated generally as 2, and in which are slidably arranged an upper sash member 3 and a lower sash member 4. The window frame 2 is shown as comprising a sill 5 mounted upon a stool 6 and connected to a metal trim 7 as by means of bolts or rivets or the like 8, the metal trim in turn being connected by any suitable means to the hull or metal plate 1; stiles 9 which are adapted to be suitably connected at their interior to a jamb or wooden trim 10, and at their exterior to a metal trim 11 which is connected by means of bolts, rivets or the like 12, to the metal plate or hull of the ship; and a head jamb 13.

Connected also to the frame and forming a part thereof, is a head plate 14 connected by means of bolts, rivets or the like 15 to a metal trim 16, which in turn is connected to the metal plate or hull of the ship. This head plate 14 bridges between the stiles 9, and at its lower edge is provided with a channel or groove member 17, adapted to receive a part of the upper sash 3 when in closed position.

The upper sash member 3 comprises an upper channel shaped rail 18 having an outwardly extending doubled-over portion 19 provided with a downwardly projecting rib 100

20 forming a channel between the same and a side wall of the channel shaped rail, for the reception of an upwardly extending rib on the head plate 14 so as to provide a tight
5 closure therebetween when the upper sash is in closed position. The lower channel-shaped rail 22 of the upper sash member is constructed similar to the upper rail and includes a doubled-over inwardly extending portion 23
10 provided with an upwardly extending rib 24 adapted to form a weather-tight closure with the upper rail of the lower sash 4. The side rails 25 are similar in construction and comprise a channel shaped rail having an outwardly extending doubled-over portion 26
15 adapted to be received in a longitudinally extending U-shaped groove or channel 27 in the stile 9.

The upper rail 28 of the lower sash 4 is
20 similar in construction to the rails 18 and 22 of the upper sash, and comprises a channel shaped member having an outwardly extending doubled-over portion 29 provided with a downwardly extending rib 30 forming
25 a channel therebetween and a side wall of the rail.

The lower rail 31 and the side rails 32 are similar in construction to the side rails 25 of the upper sash member, the side rails having an outwardly extending doubled-over portion 33 adapted to be slidably received in a U-shaped groove or channel 34 formed in the stiles 9. The U-shaped channels or grooves 27 and 34, extend for the full length
35 of the stiles, thus permitting upper and lower sash members to be raised to a position adjacent the head jamb 13. The doubled-over portion 35 of the lower rail is adapted to abut against a shoulder 36 of the sill 5, and to seat
40 in a channel or recess 37 in the sill.

In order to reinforce the sash rails and to permit the use of lighter material therein, the bottom rails and the side rails of each of the sash members is provided with a reenforcing bar 38 fitting conformably therein.
45 In order to permit proper expansion and contraction of the glass 39 in the upper and lower sashes, channel shaped sections 40 of felt or the like are placed intermediate the
50 glass and the reenforcing bar. The top rails 18 and 28 of the upper and lower sash members are made removable so as to permit efficient glazing of the sash construction. The side rails and top rails are cut on a bias as at
55 41, and a bolt, screw or the like 42 is adapted to be passed through counter-sunk openings in the upper sash rail and to threadingly engage in the reenforcing bars 38 in the side rails. Since these bars are frictionally held
60 in tight engagement in the rails, the upper rails may not be removed without a removal of the bolts 42. Strips of felt 43 are embedded in the top rails and engage the upper edge of the glass 39.

65 Felt or other weather stripping 44 is pro-

vided in each of the channels formed on the top and bottom rails wherever the same engage each other or with the window frame, so as to provide a weather-tight seal when the sashes are in closed position.

The sashes are so constructed that the upper sash 3 may not be raised without also raising the lower sash, while the lower sash may be raised independently to a position where the top rail contacts a striking bar or projection 45 connected to the top rail 18 of the upper sash by means of bolts or the like 46. If it is desired to raise the lower sash beyond this position, such lower sash, by reason of the contacting engagement of the rail 28 with the striking bar 45 will also raise the upper sash 3. By reason of this construction, it is possible to provide an opening through the window extending from the sill 5 to the head plate 14, without any obstruction therebetween. Catch or locking members 47 provided with a plunger adapted to seat in openings in the stiles 9, permit the lower and upper window to be adjusted to various heights and there held in place by the catch members 47.

In order to permit the sash members to be raised to their uppermost position, the window frame is provided with a well 48 intermediate the head plate 14 and wood trim 49, and the head jamb 13.

Although the invention disclosed has been described as adapted for ship construction, it is of course to be understood that the same is admirably adapted for use in other structures wherever a unit or self-contained window assembly having a double lift sash construction is desired.

Having thus disclosed my invention, I claim:

1. In a window construction, a slidable sash therefor, said sash being formed with channel-shaped rails, the upper one of which is removable for permitting glazing thereof from the top, a reinforcing bar positioned in said rails, and means for detachably connecting the upper rail to the reinforcing bars in the side rails.

2. In a metallic window construction, a frame therefor, slidable sashes adapted to be raised upwardly and seat within a well in the upper part of the frame, said sashes being formed with channel-shaped rails adapted to receive and retain panes of glass, the upper rail of a lower sash and the lower rail of an upper sash being provided with interengaging and interlocking portions for forming a weather-tight closure when the sashes are in lowered, closed position.

3. In a metallic window construction, a frame therefor, slidable sashes adapted to be raised upwardly and seat within a well in the upper part of the frame, said sashes being formed with channel-shaped rails adapted to receive and retain panes of glass, the upper

- rails of said sashes being removable for permitting glazing thereof from the top.
4. In a metallic window construction, a frame therefor, slideable sashes adapted to be raised upwardly and seat within a well in the upper part of the frame, said sashes being formed with channel-shaped rails adapted to receive and retain panes of glass, the upper rail of a lower sash and the lower rail of an upper sash being provided with inter-engaging and interlocking portions for forming a weather-tight closure when the sashes are in lowered, closed position, and a projection on the upper sash member adapted to be contacted by said lower sash member whereby said members may be raised as a unit.
5. In a window construction, slideable sash members therein, inter-engaging rails on said sash members for providing a weather-tight seal when said members are in closed position, and a projection provided on the upper rail of an upper member adapted to be contactingly engaged by the upper rail of a lower member when said lower member is raised, whereby said sash members may be raised as a unit by a further raising of the lower member.
6. In a window construction, slideable sash members therein, inter-engaging rails on said sash members for providing a weather-tight seal when said members are in closed position, and a projection provided on the upper rail of an upper member adapted to be contactingly engaged by the lower member when raised to a height equivalent to that of the upper member, whereby further raising of the lower member will elevate the members as a unit.
7. In a window construction, upper and lower slideable sash members therein, inter-engaging rails on said sash members for providing a weather-tight seal when said members are in closed position, and means on the upper sash member adapted to be contacted by the upper rail on said lower sash member when the latter is opened whereby a further raising of the lower sash member carries along the upper sash member so that said members may thereafter be raised as a unit.
8. In a window construction, upper and lower slideable sash members therein, inter-engaging rails on said sash members for providing a weather-tight seal when said members are in closed position, means on the upper sash member adapted to be contacted by the upper rail on said lower sash member when the latter is opened whereby a further raising of the lower sash member carries along the upper sash member so that said members may thereafter be raised as a unit, and means for retaining said lower sash member in an adjusted position.
9. In a window construction, a frame therefor including a head plate formed with a

channel, slideable sash members therein, and rails on said sash members including a rail on the upper sash member adapted to seat within said channel, and rails on the upper and lower sash members adapted to interengage whereby to provide a weather-tight seal when said members are in closed position.

10. In a metallic window construction, a frame therefor, and sashes slideable in said frame and formed with channel-shaped rails adapted to receive and retain panes of glass, certain of said rails being formed with offset and oppositely faced portions adapted to inter-engage and form a weather-tight seal when the sashes are in closed position.

11. In a metallic window construction, a frame therefor, and sashes slideable in said frame and adapted to be raised and seat within a well in the upper part of the frame, said sashes being formed with channel-shaped rails adapted to receive and retain panes of glass, certain of said rails being formed with offset and oppositely faced portions adapted to inter-engage and form a weather-tight seal when the sashes are in closed position.

12. In a metallic window construction, a frame therefor including a head plate formed with a channel, and sashes slideable in said frame and formed with channel-shaped rails adapted to receive and retain panes of glass, certain of said rails being formed with offset portions providing flanges, the flange on the upper rail of the upper sash being adapted to seat within the channel in the head plate, while the remaining flanges are adapted to inter-engage to form a weather-tight closure when the sashes are in closed position.

13. In a metallic window construction, a frame therefor including a head plate formed with a channel, and sashes slideable in said frame and formed with channel-shaped rails adapted to receive and retain panes of glass, the upper and lower rails of the upper sash and the upper rail of the lower sash being provided with projecting portions, the projecting portion on the upper rail of the upper sash being adapted to seat in the channel in the head plate when said upper sash is in closed position, and the projections on the lower rail of the upper sash and on the upper rail of the lower sash being in inter-engagement when said lower sash is in closed position.

In witness whereof, I hereunto subscribe my name to this specification.

ERNEST J. LIEBETRAU.
